[57] CLAIM

The ornamental design for a reversible microwave roasting rack, as shown and described.

DESCRIPTION

FIG. 1 is a perspective view of a reversible microwave roasting rack showing my new design; and
FIG. 2 is a plan view of a first surface thereof; and
FIG. 3 is a plan view of a second surface thereof, said second surface being the obverse of the first surface shown in FIG. 2; and
FIG. 4 is a side elevational view thereof; and
FIG. 5 is a front elevational view thereof.
